Primary Examiner — Cynthia R Underwood(74) *Attorney, Agent, or Firm* — Browdy and Niemark,
P.L.L.C.(57) **CLAIM**

The ornamental design for a bolt, as shown.

DESCRIPTION

The patent or application file contains at least one drawing executed in color. Copies of this patent or patent application publication with color drawing(s) will be provided by the Office upon request and payment of the necessary fee.

FIG. 1 is a first embodiment of a first perspective view of a bolt, showing my new design;

FIG. 2 is a bottom view thereof;

FIG. 3 is a top view thereof;

FIG. 4 is a second perspective view thereof;

FIG. 5 is side view thereof;

FIG. 6 is a third perspective view thereof; and

FIG. 7 is a second embodiment of a first perspective view of a bolt, showing my new design;

FIG. 8 is a second perspective view thereof;

FIG. 9 is a bottom view thereof;

FIG. 10 is a top view thereof;

FIG. 11 is a side view thereof; and,

FIG. 12 is a third perspective view thereof.

1 Claim, 12 Drawing Sheets
(6 of 12 Drawing Sheet(s) Filed in Color)
